UNITED STATES PATENT OFFICE.

JAY C. DYSART, OF HARRISVILLE, OHIO.

GATE.

SPECIFICATION forming part of Letters Patent No. 760,782, dated May 24, 1904.

Application filed January 28, 1904. Serial No. 190,998. (No model.)

To all whom it may concern:

Be it known that I, JAY C. DYSART, a citizen of the United States, residing at Harrisville, in the county of Harrison and State of Ohio, have invented certain new and useful Improvements in Gates, of which the following is a specification.

This invention relates to improvements in farm-gates of the folding-panel type, and aims to provide a general structure of gate having novel operating means therefor, the assembled parts of the gate being secured in a manner specially designed to increase the general efficiency thereof.

For a full description of the invention and the merits thereof and also to acquire a knowledge of the details of construction of the means for effecting the result reference is to be had to the following description and accompanying drawings.

While the essential and characteristic features of the invention are susceptible of modification, still the preferred embodiment of the invention is illustrated in the accompanying drawings, in which—

Figure 1 is a perspective view of a gate embodying the invention. Fig. 2 is a vertical longitudinal sectional view showing the arrangement or position of the gate structure preparatory to opening thereof. Fig. 3 is a vertical sectional view through an end portion of the gate, showing the arrangement of the bushings between the bars. Fig. 4 is a detail view of the take-up device connecting the lower end of the operating-lever and the take-up connection with the rear end of the gate. Fig. 5 is a detail view of the hinge in its preferred form. Figs. 6 and 7 are side elevations showing different vertical positions of the gate. Fig. 8 is a detail cross-sectional view of a modified form of bushing.

Corresponding and like parts are referred to in the following description and indicated in all the views of the drawings by the same reference characters.

In the preferred embodiment of the invention the gate is of the horizontal swinging type, being adapted for a tilting vertical move-

ment preparatory to its swinging movement in opening.

The gate is mounted for movement between gate-posts 1 and 2 in such a manner that said posts are relieved from all strain when the gate is resting in its normal position, the hinge-post being grounded in any suitable manner with reference to the mounting thereon. The gate comprises horizontal bars 3 and vertical bars 4. The vertical bars 4 are arranged at both ends and intermediate the ends of the gate and are spaced from each other, receiving the horizontal bars 3 therebetween. The bars 3 and 4 are secured together by transverse bolts or analogous fastenings 5, and bushings 6, mounted on bolts 5, are passed through bars 3, with washers 35 mounted in a like manner adjacent to and interposed between bars 3 and 4. The purpose of the bushings is threefold—to give the gate a free and easy movement, to overcome the clamping or binding effect caused by the swelling and warping of the bar members 3 and 4, and to make the gate as a whole more firm and rigid—while that of the washers is to keep the bar members 3 and 4 apart, allowing the air to circulate freely therebetween, thus preserving said parts at each intersection thereof. The gate is pivoted to the gate-post 1 by means of hinges, said hinges comprising eyebolts the shanks of which are threaded throughout the length thereof. An inner nut 8 is screwed upon the shank of the eyebolt, and clips 9 clamp the end bars upon opposite sides, as shown, the outermost of said clips being secured by means of an outer nut 10. The provision of nuts upon opposite sides of the clips 9 admits of greater clamping action in securing the hinged means to the vertical bars 4 and at the same time makes it possible to compensate for any sag or to adjust the gate as a whole longitudinally without removing the gate from the hinges. The eyebolts 7 receive the vertical portions of pivot members 11, rigidly securing same to the post 1. A pivoted bar 12, secured to the upper portion of the post 1, is adapted to engage the eyebolt of the upper hinge to prevent removal or accidental displacement of

the gate unless this member 12 is operated. The post 2 is provided with recessed members 13, which receive the extended ends of the horizontal bars of the gate when the gate is locked closed.

The lock means utilized consists of an operating-lever 14, which is pivoted between its ends to one of the lower horizontal gate-bars, as shown at 15. The operating-lever is provided 10 with a handle 16, and the body of the said lever comprises spaced bars which straddle the horizontal bars in a manner readily apparent. A latch 17 is pivoted adjacent one end between the spaced members of the body of the 15 operating-lever and is movable between certain of the horizontal bars 3 of the gate, the free end of the said latch resting upon one of the said horizontal bars. The latch 17 enters a recess 18, provided upon the inner side 20 of the gate-post 2, when locking the gate closed. The latch is guided in its movement by a U-shaped guide member 19, which cooperates with the adjacent horizontal gate-bar. The lower end of the operating-lever 25 14 is connected, by means of a flexible connection or wire, with the upper end portions of the rear vertical bars 4 of the gate, so that in opening the gate the same is given a vertical movement by the operation of the lever 30 14 rearwardly to throw the latch 17 out of engagement with the gate-post 2. In order to hold the latch 17 out of engagement with the gate-post and to hold the gate-body vertically tilted as initially actuated, the horizontal bar 3, upon which the latch rests, is provided 35 with a notch or depression 21, which is engaged by the end portion of the latch when the lever 14 reaches the limit of its movement, this action locking the lever in such position and permitting free swinging movement of the gate in either direction, the extended end portions of the horizontal bars being thrown out of the recessed members 13 simultaneously upon operation of the lever 40 14. To close the gate, it is necessary to operate a latch-bar 22, carried by the operating-lever 14, which is provided with a finger-piece 23. Upward movement of the latch-bar 22 raises the latch out of engagement with the 45 notch or depression 21, when the operating-bar may be returned to its normal position and the latch engaged with the gate-post 2 by entering the recess 18 therein. In order to increase the tension of the flexible connection 20 or to take up any slack which may be caused therein, due to continuous use, a special take-up device is provided. The said device consists of a hook-bar 24 and a take-up bar 25, the latter being mounted upon the 50 threaded end portion of the hook-bar, and adjustable by a screwing movement. The hook-bar 24 is adapted to engage a cross-bar 26 at the lower end of the operating-lever 14 inter-

mediate the spaced members of the said lever. The take-up bar 25 is provided at opposite ends with openings, the connection 20 being secured to the bar by passage through the said openings and suitably fastened. Though the manner of taking up the slack or increasing the tension as described with reference to the take-up device aforesaid is that preferably used, it will be understood that a bail mounted upon one of the horizontal bars 3 and provided with eyes receiving the spaced portions of the connection 20 may be substituted or used at the same time for the purpose set forth. The bail 27 engages notches upon the horizontal bar, which is in this instance the uppermost of these bars of the gate. It is further contemplated to lock the lever 14 in its rearward position by means of notches 28 upon the uppermost horizontal bar 3 of the gate, said lever being adapted to engage these notches. The above manner of locking the lever would be used should it be desired to give the gate a more acute angle of elevation in order that the structure may pass freely over snow-drifts or other obstructions or allow small stock to pass thereunder or should it be desired to dispense with the use of the latch and sustaining-wires and to operate the gate manually relative to the tilting thereof.

A special advantage derived from the construction of the take-up device is gained when it is desired to hold the gate open by dropping same upon the ground. When the above is done, the hook-bar 24 is disengaged from the cross-bar 26, and this permits of a dropping movement of the gate structure to cause same to rest upon the ground. The above would be done only when it becomes necessary to leave the gate permanently open or open for quite a length of time. The take-up device thus performs a double function in establishing the detachable connection between the wire and the lever and at the same time providing a take-up mechanism *per se*. When the gate is open and resting upon the ground, the strain upon the rear vertical gate-bars, as well as the hinge-post, is relieved, this being very desirable, since the greater portion of the weight is sustained by the connection 20.

Having described the preferred construction of my flexible gate, I do not wish to be limited to the precise construction set forth, as various changes in the details may be made, as will be clear, without departing from the spirit of the invention. 115 120

A modified form of bushing 6 in the form of a spring may be utilized instead of a solid bushing, if desirable.

Having thus described the invention, what is claimed as new is—

1. In a gate, the combination with an operat-

ing-lever pivoted between its ends to the gate adjacent the front end thereof, a hook-bar detachably secured to the lower end of the operating-lever, and a connection between the hook-bar and the upper rear end of the gate.

5. In a gate, the combination with an operating-lever pivoted between its ends, a hook-bar detachably secured to the lower end of the operating-lever, a take-up bar adjustable upon the hook-bar, and a connection between the take-up bar and the upper rear end of the gate.

10. In a gate, the combination with an operating-lever disposed at the forward end of the gate and pivoted between its ends thereto, a threaded hook-bar engaging the lower end of the operating-lever, a take-up bar adjustable upon the threaded portion of the hook-bar, and

a connection between the take-up bar and the upper end of the gate.

15. In a swinging gate, the combination with a lever mounted upon the swinging end of the gate and pivoted intermediate its ends, a tilting connection between the lower end of the lever and the upper rear end of the gate, a latch pivoted to the lever, and a U-shaped 25 guide-bar carried by the latch for the purpose described, said guide member engaging one of the gate-bars.

In testimony whereof I affix my signature in presence of two witnesses.
